OIL CUP

Filed Oct. 27, 1928

Inventor

Lloyd B. Jones,

By *W. S.*

Attorney

UNITED STATES PATENT OFFICE

LLOYD B. JONES, OF COLUMBUS, OHIO

OIL CUP

Application filed October 27, 1928. Serial No. 315,462.

This invention relates to the subject of lubrication and has for its primary object an improved oil cup which has facilities for receiving the oil to be replenished in the cup together with means for keeping the oil placed therein, free from dust, cinders and other foreign material usually found abundant around a steam locomotive while the same is in motion.

Another object of this invention is to provide an opening in the top of the oil cup through which an oil can spout is permitted to protrude when oil is placed in the cup together with means for automatically closing the said opening when the oil can spout is withdrawn from the cup.

A further object of this invention is to provide a gravity operated oil can spout door, positioned in the lid of the oil cup and having means for freely swinging when engaged by the spout of the oil can.

A still further object of this invention is to provide an oil cup lid having a housing carried by the lid with means for permitting an oil can spout door to swing within the housing.

With these and many other objects in view which will become more readily apparent as the nature of the invention is better understood, the same consists in the novel construction, combination and arrangement of parts as will be hereinafter more fully pointed out, illustrated and claimed.

It will be quite readily understood by those skilled in the art to which this invention belongs that the same is quite susceptible to various changes and modifications without departing from the spirit or scope of the invention, but a preferred and thoroughly practical embodiment of the invention is shown in the accompanying drawings in which:

Fig. 1 is a plan view of my improved oil cup.

Fig. 2 is an elevational view of the cup shown in Fig. 1.

Fig. 3 is a plan view of the oil cup body with the top removed.

Fig. 4 is an elevational view of the cup body shown in Fig. 3 of the drawings.

Fig. 5 is a plan view of the oil cup top having the body portion of the cup removed.

Fig. 6 is an elevational view of the oil cup top, showing the oil can spout door housing and the gravity actuated door swung open in position to permit oil to be placed in the cup.

Fig. 7 is an end elevational view of the oil cup top shown in Fig. 6 of the drawings.

Fig. 8 shows a plan and elevational view of the oil discharge pin, as shown in operative position in Fig. 2 of the drawings.

Fig. 9 shows plan and elevation views of an helical spring used between the top of the oil cup lid and the wing nut on the top of the oil adjusting pin as illustrated in Fig. 2 of the drawings.

Fig. 10 shows plan and edge views of a washer positioned between the bottom of the wing nut on the oil adjusting pin and the top of the helical spring shown in Fig. 9 of the drawings.

Fig. 11 shows a plan, edge and end view of the gravity actuated oil cup door, adapted to be actuated by the spout of the oil can when replenishing the oil in the cup, and closed by gravity when the spout of the oil can is withdrawn.

Fig. 12 is an end elevational view of a modification of the oil cup top shown in Fig. 7 of the drawings.

Fig. 13 shows a plan view of a modified form of the gravity actuated door shown in Fig. 11.

Similar reference numerals refer to similar parts throughout the several figures of the drawings.

The present invention was primarily made to be used on the crosshead guides of steam locomotives and consists essentially of a body portion designated by the numeral 10, having integral means 11 for attaching the cup body to the guides of the steam locomotive.

The body portion 10 is further provided with a pendent centre annular boss 12, through which an opening 13 is drilled, to provide means for permitting the oil to escape from the cup after being released therefrom. The pendent boss 12 is prefer-

ably made cone-shaped to provide a dripping edge 14 as shown in Fig. 4 of the drawings.

In order that the oil in the body of the cup may be discharged in a fixed and predetermined quantity a conical shaped oil control pin 15 is provided, having the lower end 16 adjacent the conical portion 15 threaded such as to coact with a threaded annular opening 17 in the cup body as shown in Fig. 4 of the drawings.

In order that the oil control discharge pin 15 may be rotated to permit fine adjustment of oil discharge opening, a winged end 18 is provided. After the proper adjustment of oil opening has been made it is necessary that this adjustment be maintained and to this end I provide a helical spring shown positioned between the top 20 of the oil cup lid 21 and a washer 22 positioned above the spring 19 immediately below the winged end 18 of the oil control pin 15 as shown in Fig. 2 of the drawings.

The oil cup lid 21 is further provided with a housing 23, which is shown rectangular in shape, and carries a hinged gravity actuated door 24, adapted to swing on a pin 25, shown positioned in the housing 23, Fig. 6, of the drawings.

The door 24 shown in position in Fig. 6 of the drawings is provided with a depression 26 against which the oil can spout is adapted to impinge when the cup is being filled with oil as the door is swung inward by the can spout and when the spout is withdrawn the door swings by gravity to a vertical position, closing the opening in the housing, thus preventing in a very practical way the adulteration of the oil in the cup by the accumulation of cinders and dirt and all material foreign to the oil.

By reference to Fig. 11 of the drawings it will be observed that the perforation adapted to receive the pin 25 is positioned in different plane from that in which the centre of gravity is positioned, this construction readily permits the door 24 to remain closed while the locomotive is in motion, and the centre of gravity raised before the door is open such as to receive the oil can spout.

Having thus described my invention what I claim and desire to be secured by Letters Patent is:—

1. In an oil cup, a cup body, a removable cap for said body, a housing extending upwardly from said cap, one side of said housing being open and the bottom of said housing being in communication with the cup body, and a closure member pivoted at its top to a top portion of said housing whereby it is gravity actuated to close the open side of said housing.

2. In an oil cup, a cup body, a removable cap for said body, a housing extending upwardly from said cap, one side of said housing being open and the bottom of said hous-

ing being in communication with the cup body, a closure member pivoted at its top to a top portion of said housing whereby it is gravity actuated to close the open side of said housing, said closure member being of a size to fit the open side of the housing and to lie normally with its outer face flush with the outer face of the housing, and a stop formation on said closure member for engagement with the inner face of the housing to prevent the closure member from swinging outwardly through the open side of the housing.

3. In an oilcup, a cup body, a removable cap for said body, a housing extending upwardly from said cap, one side of said housing being open and the bottom of said housing being in communication with the cup body, and a closure member pivoted at its top to a top portion of said housing whereby it is gravity actuated to close the open side of said housing, the outer face of said closure member being provided with a recess into which the end of an oil can spout is adapted to be engaged to effect opening of said member by pressure exerted thereagainst by the spout.

In testimony whereof I affix my signature.

LLOYD B. JONES.
